BOTTLE COLLAR

Claude D. Painter, San Francisco, Calif., assignor
to Harry F. Borden, San Francisco, Calif.

Application September 7, 1938, Serial No. 228,817

7 Claims. (Cl. 40—4)

The present invention relates to bottle collars or devices formed of paper or like material and shaped to encircle bottle necks, there to display printed advertising matter which usually has reference to the contents of the bottle or other products merchandised by the advertiser.

Many forms of bottle collars, or "bottle cuffs," as they are sometimes termed, are in general use at the present time, and they usually comprise tapered rings which slip over the tops of the bottles and are supported by the outwardly flaring side walls of the bottles at the point where the neck of the bottle flares to meet the body portion thereof. These collars are formed from flat paper blanks, generally cut to an arcuate shape, and the ends of these blanks are brought together to form a device of circular tapered shape. The device is retained in this shape by fastening together the ends of the blank with an adhesive or with any one of various forms of interlocking connections produced by cutting slits and notches in the paper.

The present invention contemplates the formation of a bottle collar from a single flat blank of paper, so shaped that it may be folded or set up without the necessity of forming any connections between loose ends, and in which the folding operation itself serves to retain the collar in proper shape and to present an attractively-shaped conveniently positioned panel for the display of printed advertising matter.

It is the object of the present invention to provide a bottle collar which may be set up for application to a bottle without the necessity of fastening together any parts thereof, but by a simple folding operation; to provide a bottle collar formed of a flat blank capable of being folded to assume a circular tapered shape and firmly retained in such shape by interfolding of its own parts; and to provide a bottle collar which is simple and inexpensive to manufacture and set up, and which presents a neat and attractive device for the display of printed matter.

One form of the invention is shown for purposes of illustration in the accompanying drawing, and detailed reference to the drawing is made in the following specification wherein further objects and advantages of the invention are set forth.

In the drawing—

Fig. 1 is a front elevation of a bottle collar embodying the present invention illustrated in place on a bottle;

Fig. 2 is a side elevation of the same;

Fig. 3 is a plan view of a bottle collar of the type shown in Figs. 1 and 2, illustrated as partially set up; and

Fig. 4 is a plan view of a paper blank from which a bottle collar is formed.

The invention comprises a flat paper blank cut in such a manner that it may be set up into a tapered ring-like body member adapted to encircle the bottle, and a panel of paper so connected and supported by the tapered body member that it will stand out from the bottle in a conspicuous position. In the accompanying illustrations this panel is shown as cut to assume the likeness of a bow-tie. This shape is, however, illustrative of but one form that the panel may assume, and it is to be understood that the panel may be given any desired shape suitable to the requirements of artistic design or advertising display. For example, the panel may be cut and printed to represent a dish of ice cream or fruit, or a package of cheese, butter or whatever products it may be desired to advertise.

The invention is illustrated in the drawing as comprising a body member 10 which forms the main portion of the tapered ring which encircles the bottle, and a display panel 11 which, in the present instance, is shaped to represent a bow-tie. A pair of connecting members, which may be referred to as wings 12, serve to connect the body member 10 and the display panel 11 along lines 13 and 14, which lines are preferably scored or perforated to facilitate bending. A locking flap 15 extends from the lower edge of the display panel 11 to which it is connected along the line 16, which is also perforated or scored for bending.

Fig. 4 illustrates a flat blank as it would appear upon being stamped from a plain sheet of paper, and Fig. 3 illustrates the manner in which this blank is set up to form a bottle collar which retains itself in its set-up position. As illustrated in Fig. 3, the blank is bent inwardly along the lines 14 to impart a tapered or frusto-conical shape to the body member 10 and to position the display panel 11 directly in front thereof. The locking flap 15 is then bent back or inwardly along the line 16 and, upon completion of the setting-up operation, the first part of which is illustrated in Fig. 3, the locking flap 15 will assume a position within the tapered circular body member 10. This position of the locking flap

serves to prevent unfolding or straightening out at the lines 13 and 14, such as would necessarily accompany the flattening out of the tapered body member, and the device is therefore securely locked in its set-up position even before it has been applied to the bottle. In the set-up position the locking flap 15 will conform to the inner contour of the tapered body member and will also serve to fill in or cover a V-shaped gap occurring between the ends of the body member. The display panel occupies a position directly in front of the body member, and it is substantially tangent to the outer surface of the body member.

15 The collars constructed in the manner just described are easily set up by simple folding operations, and will retain their shape without the necessity of gluing or locking together the 20 free ends of a paper blank. The panel 11 stands out from the tapered body member and from the bottle to which it is applied, although it assumes a slight curve. The construction is such that the collars, after having been set up, may be 25 telescoped or nested to form convenient stacks from which they may be removed one at a time when they are being applied to bottles. They nest within each other very readily, as the wings 30 12 and outer ends of the panel 11 are free to flex backwardly and lie closely adjacent the tapered body member.

Advertising matter may be printed on the entire surface of the device. Subject matter which 35 it is most desired to bring to the attention of the purchaser may be printed on the face of the display panel 11. The locking flap 15 affords additional space for printed matter, such as recipes which call for the product contained in the bottle, or other products sold by the same 40 merchant. The space for printed matter which is provided by the flap 15 may be enlarged by extending or adding to the length of the flap at its lower edge, and the extended portion may be folded over so that it will be accommodated with- 45 in the same space as that occupied by the flap of the dimensions shown in the drawing. The outer surface of the panel 11 is valuable for calling attention to the advertising matter printed on the other portions of the device. For example, 50 in the form of the invention here shown, the necktie-shaped panel may bear a printed legend to the effect that the products of the advertiser may be "tied in" with attractive menu plans and bear reference to menus and recipes printed on 55 other parts of the device.

It is to be understood that the foregoing description and drawing are illustrative of but one form of the invention, which is not limited thereby but which may be varied within the scope of 60 the appended claims.

Having thus described my invention, what I claim and desire to secure by Letters Patent is—

1. A bottle collar comprising an arcuate tapered member adapted to embrace a bottle, a display panel connected thereto by foldable wing members, and a locking flap attached to the display panel and foldable to a position within the tapered member. 5

2. A bottle collar comprising an arcuate tapered member adapted to embrace a bottle and 10 formed by bending a paper-like blank, a display panel formed as a part of said blank and connected by foldable wing members to be supported by the tapered member, and a locking flap carried by the display panel and foldable into 15 the tapered member.

3. A bottle collar formed from a flat blank 20 cut to form a body member, a display panel, a pair of wings connecting the body member and display panel along foldable lines, and a locking flap connected to the display panel whereby the body member may be bent to a tapered arcuate shape with the display panel supported exteriorly thereof by said wings, and the locking flap folded to a position within the tapered body member. 25

4. A bottle collar folded from a single blank 30 of flat paper-like material comprising an arcuate collar member substantially to surround the bottle neck, a display panel disposed between the ends of the collar member and supported exteriorly of the collar member by a pair of wing members connecting it therewith, and a flap foldable from an edge of said panel to the interior of the collar member to retain the collar in its folded position. 35

5. A bottle collar of the character described 40 comprising an arcuate member folded to embrace the neck of a bottle, a pair of wings folded outwardly from the ends of said member, a panel connecting the ends of said wings to overlie the space between said ends and means for retaining 45 said collar in folded position. 50

6. A bottle collar of the character described 55 comprising an arcuate member folded to embrace the neck of a bottle, a pair of wings folded outwardly from the ends of said member, a panel connecting the ends of said wings to overlie the space between said ends, and a flap foldable from an edge of said panel to underlie said space and retain the collar in folded position. 60

7. A bottle collar of the character described 65 comprising an arcuate member folded to embrace the neck of a bottle, a pair of wings folded outwardly from the ends of said member, a panel connecting the ends of said wings to overlie the space between said ends and means comprising a flap foldable from an edge of said panel to the interior of the collar member for retaining said collar in folded position. 70
